UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAG.

Application filed May 2, 1925. Serial No. 27,338.

My invention relates to bags produced from a continuous tube of bag material and closed at the ends by seams; and has particular reference to bags of such material or 5 size as to make important a hem or fold in connection with the end seam.

My invention is diagrammatically illustrated in the accompanying drawings; where-in Fig. 1 is a diagrammatic elevation of apparatus which may be used in producing my bag; Fig. 2 is an elevation of the tube from 10 which the bag is formed; Fig. 3 is an elevation similar to Fig. 2 but showing in partial section folds formed in the tube; Fig. 4 is an enlarged detail side view of parts showing a 15 filled bag with its ends closed; Fig. 5 is a front view of parts shown in Fig. 4; Fig. 1^a is a view similar to a portion of Fig. 1, but showing a different fold; Fig. 3^a is similar to Fig. 3, showing another form of fold. 20

I have shown a roll A of any suitable bag fabric, which has its two edges brought together around a form tube B and permanently fastened together by a seam-forming 25 device C, so as to form a tube D from which bags may be made. The tube is turned to bring the seam inside by drawing it down through the inside of the form tube B and outside of a filling tube B', through which 30 successive charges of material may be fed into the tube.

After a charge has been fed into the tube, 35 folds E and F are formed in the tube above the charge. These folds may take any suitable form, such as the inward telescoping folds of Figs. 1, 3, 4 and 5, or the outward telescoping fold of Fig. 3^a, or the folds shown in Fig. 1^a.

In making the folds shown in Figs. 1, 3, 40 4 and 5, the folds E and F are connected by an inner tube portion G, which extends across the space H between the folds. In Fig. 1 there is shown diagrammatically a sewing machine L having needles M, M 45 adapted to sew seams K, K through folds E, F, and having a cutter N' adapted to sever the connecting portion G of the tube along line N, the cutter passing through the space H between the folds.

In Fig. 1^a folds E', F' are shown which 50 are made by folding both walls of the tube on the side towards the needle, so that the connecting portion G' is on that side of the tube. This kind of fold is sometimes easier 55 to form than the telescoped fold. In the

usual form of sewed seam K', K' there is more thread on the side away from the needles than on the side towards the needles, so that it is preferable to have the folds on the side towards the needles when they are 60 formed on one side only.

In Fig. 3^a folds E², F² are shown which are made in the same way as folds E and F except that they are folded outward instead of inward so that connecting portion G² is 65 on the outside instead of being on the inside like connecting portion G.

The telescoping folds are symmetrical folds which strengthen both sides alike, and are desirable for that reason; but the most 70 important feature of the folds is that they be so made that they can be formed in a tube before the tube is severed. It is noted that, in each of the folds shown, the fabric doubles back upon itself and then continues 75 in the same direction as before, resulting in the fold of each layer of fabric being substantially Z shaped in cross-section, and the severed edges extend as far as, or a little 80 beyond, the folds at the ends of the bags, where the fabric is cut between the bags.

One method of making the fabric into a tube and one way of filling charges into the tube, is shown, but it is not material how the tube 85 is formed, and any suitable method may be used for filling the bags. I contemplate particularly making filled hemmed bags, but in the case of valve bags, or bags intended to be filled through a small aperture, the folds 90 could be sewed at both ends of the bag while the bag was still empty, leaving it for a subsequent operation to insert a filling tube between the folds, or elsewhere, and thus fill the bag.

I claim:

1. A bag comprising a body, the end section of the body being inwardly telescoped, and a seam across the end of the body through the telescoped portion, the edges of the bag projecting beyond said telescoped portion.

2. A bag comprising a body portion, the ends of said body being telescoped inwardly, and seams across the ends of the bag through such telescoped portions, the edges of the bag projecting beyond said telescoped portions.

3. A bag comprising a body, the end section of the body being telescoped, and a seam across the end of the body through the tele-

2
scoped portion, the edges of the bag projecting beyond said telescoped portion.

4. A bag comprising a body portion, the ends of said body being telescoped, and 5 seams across the ends of the bag through such telescoped portions, the edges of the bag projecting beyond said telescoped portions.

5. A bag made from a bag-tube, comprising a bag portion, the bag tube being telescoped to form double folds at the ends of the bag, and seams across the ends of the bag through such telescoped portions, the bag-tube being severed adjacent the end of the bag.

10 15 6. A bag made from a section severed from

a bag-tube, the bag-tube being folded at the ends of the bag, and seams across the ends of the bag through such folded portions, and the severed edges of the bag projecting at the ends of the bag beyond said folds. 20

7. A bag made from a section severed from a bag-tube, the bag-tube being folded at the end of the bag so that the fabric returns upon itself and forms a fold substantially Z shaped in cross-section, and a seam across the end of the bag through such folded portion. 25

In testimony whereof I have hereunto signed my name to this specification.

ADELMER M. BATES.
